VALVE FOR ROCK DRILLS

William A. Smith, Sr., Athens, Pa., assignor to
Ingersoll-Rand Company, Jersey City, N. J., a
corporation of New Jersey

Application April 2, 1936, Serial No. 72,318

2 Claims. (Cl. 121—28)

This invention relates to rock drills, and more particularly to a distributing valve for fluid actuated rock drills.

One object of the invention is to assure rapid and positive action of the valve, and another object is to assure a heavy and forceful blow of the percussive element against the working implement.

Other objects will be in part obvious and in part pointed out hereinafter.

In the drawing accompanying this specification and in which similar reference numerals refer to similar parts,

Figures 1 and 2 are longitudinal views, in section, of a rock drill constructed in accordance with the practice of the invention and showing the valve in its limiting positions.

Referring more particularly to the drawing, 20 designates the rock drill comprising a cylinder 21 which is bored to form a piston chamber 22 containing a reciprocating hammer piston 23. The piston chamber has a free exhaust port 24 which is controlled by the piston 23.

The piston shown is of the differential type, having a stem 25 on its front end which extends slidably through a washer 26 in the front end of the cylinder to deliver blows against a working implement (not shown).

In the rear end of the cylinder 21 is an enlarged bore 27 to accommodate a valve chest 28 comprising, in the present instance, a series of plates 29, 30, 31 and 32 which are arranged in the order named from the outer end of the bore 27, the plate 32 being the innermost of the group and forms a closure for the rear end of the piston chamber 22.

The plates 30 and 31 are suitably bored to form a valve chamber 33, and on the plate 29 is an extension 34 that extends through the plates 40 30 and 31 and forms an inner bounding surface for the valve chamber 33. The valve chamber is thus of annular shape and contains a valve 35 of the sleeve type for distributing pressure fluid to the ends of the piston chamber to actuate the 45 piston. Such pressure fluid is conveyed into the rear end of the piston chamber by an inlet passage 36 in the plate 32 and opening into the front end of the valve chamber, and an inlet passage 37 in the cylinder 21 and the valve chest 28 conveys pressure fluid from the rear end of the valve chamber 33 to the front end of the piston chamber.

The pressure fluid employed for this purpose is conveyed to the valve chamber 33 by a supply 50 passage 38 which communicates with the front

and rear ends of the valve chamber through passages 39 and 40, respectively. The pressure fluid may be introduced directly into the supply passage 38 from a throttle valve 41 housed by a back head 42 forming the rearmost casing part of the rock drill.

Intermediate the ends of the valve is an external flange 43 of which the front and rear surfaces constitute actuating surfaces 44 and 45, respectively. The surfaces 44 and 45 are subjected intermittently to pressure fluid for actuating the valve. That acting against the surface 44 for that purpose is conveyed thereto by a kicker passage 46 opening into the piston chamber 22 at a point forwardly of the exhaust port 24, and a 10 kicker passage 47 leads from the piston chamber 22, at a point rearwardly of the exhaust port 24 to convey pressure fluid to the actuating surface 45.

To the end that the value of the pressure fluid supplied to the actuating surfaces 44 and 45 may be immediately reduced after shifting the valve the front and rear ends of the portion of the valve chamber containing the flange 43 are provided with vents 48 which open into an exhaust passage 49, in the valve chest, leading to the atmosphere.

In the form of the invention illustrated the front and rear ends of the valve serve as holding surfaces 50 and 51 against which the pressure fluid flowing from the supply passage 38 to the inlet passages acts for holding the valve in its limiting positions. The surfaces 50 and 51 also serve as seating portions of the valve. They cooperate with seating surfaces 52 and 53 on the plates 32 and 30 to limit the travel of the valve and to seal the ends of the valve chamber from the inlet passages.

To the end that the piston 25 may deliver a powerful blow against the working implement and travel its full nominal stroke in both directions unhampered by compression, the extension 34 is provided with front and rear relief passages 54 and 55 communicating with the inlet passages 36 and 37, respectively, and opening into the periphery of the extension 34. The extension 34 is further provided with a discharge passage 56 which opens into the periphery of the extension 34 at a point intermediate the passages 54 and 55 and extends through the extension 34 and the plate 29 to the atmosphere. The passages 54 and 55 are placed alternately in communication with the passage 56 by an internal annular groove 57 in the valve 35.

In the form of the invention shown the exten- 55

sion 34 serves both as a guide member for the valve and for a rifle bar 58 which extends rotatably therethrough and interlockingly engages the piston 23 in a well known manner. The rifle bar has the usual head 59 which carries spring-pressed plungers 60 adapted to engage the teeth 61 of a ratchet ring 62 in the back head 42 for effecting a step-by-step rotary movement of the piston and the implement which it actuates, in 10 to a manner well understood.

The operation of the device is as follows: With the valve 35 and the piston 23 in the rearmost limiting positions illustrated in Figure 1, pressure fluid flows through the passage 39 across the 15 holding surface 58 of a valve, thereby holding the valve immovable, thence passes through the inlet passage 36 into the rear end of the piston chamber and actuates the piston on its working stroke. When, during this stroke, the piston overruns the 20 exhaust port 24 a portion of the air in the front end of the piston chamber is expelled through the inlet passage 37, the relief passage 55, the groove 57 and the passage 56 to the atmosphere instead of being compressed. Air in advance of the piston 25 will continue to flow from the front end of the cylinder until the valve is again shifted forwardly and only the air then remaining in the front end of the piston chamber will be compressed.

30 The shifting of the valve to the new position will occur immediately before the rear end of the piston chamber is opened to the atmosphere and follows the uncovering of the kicker passage 47 by the piston. When this kicker passage is uncovered pressure fluid flows to and acts against the actuating surface 45 and throws the valve 35 forwardly against the seating surface 52. Pressure fluid will then flow from the passage 48 across the holding surface 51, thence through the 35 inlet passage 37 into the front end of the piston chamber and, in passing over the holding surface 51, will hold the valve firmly against the seating surface 52.

The pressure fluid admitted into the front end 45 of the piston chamber drives the piston rearwardly, and after the piston covers the exhaust port 24 a portion of the air in the rear end of the piston chamber is expelled through the relief passage 54, the groove 57 in the valve, thence 50 through the passage 56 to the atmosphere.

As the piston proceeds rearwardly it uncovers the kicker passage 46. Pressure fluid then flows to the actuating surface 44 and again throws the valve rearwardly to a position in which the holding surface 51 rests upon the seating surface 53 to seal the rear end of the valve chamber, thus completing the cycle of operations.

I claim:

1. In a fluid actuated rock drill, the combination of a casing having a piston chamber and a piston therein, an exhaust port for the piston chamber, a valve chest having a valve chamber and a supply passage, front and rear inlet passages leading from the valve chamber to the piston chamber, a valve in the valve chamber to control communication between the supply passage and the inlet passages, opposed actuating surfaces on the valve intermittently exposed to pressure fluid valved by the piston for throwing the valve, holding surfaces on the ends of the valve exposed to pressure fluid flowing to the inlet passages for holding the valve, seating surfaces in the valve chamber for the holding surfaces, a guide member within the valve, and passages in the guide member controlled by the valve for relieving compression from the piston chamber.

2. In a fluid actuated rock drill, the combination of a casing having a piston chamber and a piston therein, an exhaust port for the piston chamber, a valve chest having a valve chamber and a supply passage, front and rear inlet passages leading from the valve chamber to the piston chamber, a valve in the valve chamber to control communication between the supply passage and the inlet passages, opposed actuating surfaces on the valve intermittently exposed to pressure fluid valved by the piston for throwing the valve, holding surfaces on the valve exposed to pressure fluid flowing to the inlet passages for holding the valve, seating surfaces in the valve chamber for the holding surfaces, a guide member within the valve having an exhaust passage, relief passages in the guide member communicating with the inlet passages, and an internal groove in the valve to establish communication between the relief passages and the exhaust passage for relieving compression from the piston chamber.
